UNITED STATES PATENT OFFICE.

GEORGE H. SHANE, OF DENVER, COLORADO, ASSIGNOR TO THE STEEL RAILWAY TIE AND APPLIANCE COMPANY, OF DENVER, COLORADO, A CORPORATION OF COLORADO.

RAILWAY-TIE AND RAIL-CHAIR.

1,106,415.

Specification of Letters Patent. Patented Aug. 11, 1914.

Application filed February 16, 1914. Serial No. 818,831.

To all whom it may concern:

Be it known that I, GEORGE H. SHANE, citizen of the United States, residing in the city and county of Denver and State of Colorado, have invented certain new and useful Improvements in Railway-Ties and Rail-Chairs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in railway ties and rail chairs, whereby the track rails are secured to the ties.

In my improvement the ties have the shape of I-beams, and the chair members are provided with depending flanges adapted to engage the tops of the ties on opposite sides, the said flanges extending below the top and being connected by bolts passing through the flanges and the web of the tie. These rail chair members, above the tie, embrace the track rails on opposite sides. The flanges of the chair members, or parts thereof, engage recesses formed in the opposite flanges of the top of the tie.

A number of different forms of the construction are illustrated in the drawing in order to indicate that the construction is not limited to any particular or exact form of construction except so far as the general idea is concerned.

Having briefly outlined my improved construction, I will proceed to describe the same in detail, reference being made to the accompanying drawing, in which is illustrated an embodiment thereof.

In this drawing, Figure 1 is a top plan view of a pair of ties, illustrating my improved construction, the same being shown in connection with track rails. Fig. 2 is a section taken on the line 2-2, Fig. 1. Fig. 3 is an elevation, looking in the direction of arrow 3, Fig. 2. Fig. 4 is a section taken on the line 4-4, Fig. 2. Fig. 5 is a perspective view of one of the rail chair members. Fig. 6 is an underneath view of the same. Fig. 7 is a top plan view of one of my improved ties. Fig. 8 is a fragmentary view of one of the ties, shown on a larger scale. In this view a slightly different form of construc-

tion is illustrated. Fig. 9 is a view similar to Fig. 3, but showing the form of tie and rail chair illustrated in Figs. 8 and 10. Fig. 10 is an underneath view of one of the rail chair members shown in Fig. 9. Fig. 11 is a top plan view of still another form of construction, the track rail being indicated by dotted lines. Fig. 12 is a fragmentary top plan view of still another form of my improved tie. Fig. 13 is a perspective view in detail of a rail chair member of the construction shown in Fig. 11. Fig. 14 is a fragmentary side view, showing a tie of the construction illustrated in Fig. 12, and rail chair members of the construction illustrated in Fig. 13. In this view the track rail is indicated by dotted lines. Fig. 15 is a view similar to Fig. 11, but showing still another modification. Fig. 16 is a perspective view of a rail chair member of the construction illustrated in Fig. 15.

The same reference characters indicate the same parts in all the views.

Referring first more particularly to Figs. 1 to 7, inclusive, let the numeral 5 designate a railway tie which is preferably composed of metal and has the shape of an I-beam. As illustrated in the drawing, the bottom flanges 6 extending on opposite sides of the web 7 are somewhat longer than the corresponding top flanges 8 of the structure. The top flanges, as shown in this form of construction, are provided on opposite sides with recesses 9 adapted to receive lugs 10 projecting downwardly from the under surface of rail chair members 12 which are also provided with depending flanges 13 which extend below and outside of the lugs 10. These flanges also embrace the top flanges of the tie on opposite sides, and extend below the same, their lower portions having perforations 14 adapted to receive bolts 15 which are also passed through registering openings 16 formed in the web 7 of the tie. These bolts are secured by nuts 17. The rail chair members in this form of construction have floor parts 18 which extend transversely of the tie and are engaged by the under surface of the flanges 19 of the base of the track rail 20. Above the floor part 18 is a rail-flange-engaging part 21 whose lower surface 22 engages the upper surface of the flange 19 of the rail while a vertical part 23 engages the web 24 of the rail. These two rail chair members which embrace the rail

on opposite sides constitute a rail chair. The two members tightly engage the rail on opposite sides and maintain the latter in place against possible lateral movement. 5 With this construction it is impossible for the rails to spread, since the rail chairs are tightly secured to the ties, not only by the bolts 16, but also by the lugs 10 which are fitted into the recesses 9 of the top flanges of 10 the tie.

In the form of construction shown in Figs. 8 to 10, inclusive, instead of open recesses 9, recesses or openings 25 are formed in the flanges 8 of the tie, being located 15 between the outer edges of the flanges and the web. Hence, the only difference between this form and that shown in Figs. 1 and 7 is that the recesses 25 are closed on all sides, while the recesses 9 are open on one 20 side. The rail chair members for use with this form of construction have lugs 26 arranged to fit the openings 25, the lugs being spaced from the depending flanges 13 of the rail chair member to correspond with 25 the space between the openings 25 and the outer edges of the flanges 8 of the tie which the depending flanges 13 of the rail chair members engage. In other respects this construction is precisely the same as 30 that shown in Figs. 1 to 7, inclusive.

In the form of construction shown in Figs. 11, 12, and 13, instead of a number of recesses 9 formed in the flanges 8 of the tie on opposite sides, a single elongated 35 recess 27 is employed. These recesses 27 are arranged on opposite sides of the top of the tie, and are of sufficient length to receive depending flanges 28 of rail chair members 29 of the construction shown in 40 Fig. 13. In other words, these flanges 28 of each member 29 have a width equal to half the length of the recesses 27, so that when the two members are assembled in connection with the track rail and the tie, the 45 flanges 28 of the two members exactly fill the recesses 27 of the tie in this form of construction. The flanges 28 of each member 29 are connected by a floor piece 30, the two floor pieces of the two members 50 forming a support for the track rail and being of the same width as the base of the rail. From the outer edges of these floor pieces, rail-flange-engaging parts 31 are provided. These rail chair members are 55 bolted to the tie in substantially the same manner as in the forms of construction heretofore employed—that is to say, each flange 28 is provided with a perforation 32 adapted to receive a bolt 33 which also 60 passes through the web 7 of the tie, the bolts being secured by nuts 34.

In the form of construction shown in Figs. 15 and 16, the rail chair members 35 are provided with depending flanges 36 made somewhat longer than the cor-

responding flanges of the form of construction shown in Fig. 13. In other words, the flanges 36 extend beyond the rail-flange-engaging member 37 and are connected beyond said member by a transverse part 70 38. Furthermore, the inner extremities of the flanges, or the portions located underneath the part 38, are not connected by a floor piece as shown in the other forms of construction. The flanges 36 are adapted 75 to enter elongated openings formed in the top flanges 8 of the tie, said openings being double the length of a flange 36, so that the two flanges of the two rail chair members just fill the opening. 80

From the foregoing description the use of my improved construction will be readily understood, and need not be explained further in detail.

Having thus described my invention, what I claim is:

1. The combination of a tie, including a web and top flanges extending in opposite directions therefrom, the said flanges having recesses, a rail chair composed of two 90 companion members having depending flanges adapted to engage and extend below the top of the tie on opposite sides, the chair members having lugs adapted to enter said recesses in the top flanges of the 95 tie, and bolts passing through the flanges of the chair members and the web of the tie, the chair members having parts engaging the base of the rail above the tie and on opposite sides. 100

2. The combination of a tie having a vertically disposed web and top and bottom flanges extending therefrom on opposite sides, rail chair members having parts extending above the tie, which embrace the 105 rail on opposite sides, flanges extending below the top of the tie and embracing the top flanges of the latter on opposite sides, the rail chair members having floor pieces which connect the depending flanges and 110 extend underneath the track rails, the floor pieces having depending lugs and the top flanges of the tie having recesses adapted to receive said lugs, and suitable means engaging the flanges of the chair members and 115 the web of the tie for securing the chair members and tie in the assembled relation, substantially as described.

3. The combination of a tie, including a web and top flanges extending in opposite 120 directions therefrom, the said flanges having their edges recessed, a rail chair composed of two companion members having depending flanges adapted to engage said recesses and extend below the top of the tie on opposite sides, and bolts passing through the flanges of the chair members and the web of the tie, for the purpose set forth.

4. The combination of a tie, including a 130

web and flanges extending from the top thereof in opposite directions, and rail chair members having depending flanges, the edges of the top flanges of the tie on opposite sides having recesses therein which the flanges of the chair members engage, whereby the rail chair members are locked against longitudinal movement on the tie, the rail chair members having parts above the tie

which engage the base of the track rails on opposite sides.

In testimony whereof I affix my signature in presence of two witnesses.

GEORGE H. SHANE.
